AIR CONDITIONING, HEATING, AND
COOLING UNITSFred M. Young, Racine, Wis., assignor to Young
Radiator Company, Racine, Wis.

Application March 9, 1935, Serial No. 10,221

3 Claims. (Cl. 257—137)

The invention relates to new and useful improvements in a unitary means for room heating, cooling and air conditioning for human comfort, the device being adapted to be located in any desirable position in the room and act to condition the air passed therethrough in an advantageous manner.

An object of my invention is to provide a novel housing having means whereby the front panel may be easily removed to thereby provide means for conveniently attaching and detaching the operating units and make them easily accessible.

A further object is to provide means whereby the air may be discharged fan like, to thereby spread the air so discharged over a wide area as it passes into and across the upper portion of the room, thus to cause all of the air in the room to be moved and returned to the unit, and to prevent air pockets or eddy currents.

Another object is to suitably position a temperature transfer core in the housing, having means whereby when operating during moderate outside temperatures, the air, passing therethrough, will all be equally affected and the heating or cooling medium will be in counter heat transfer contact with the air.

A further object is to provide a novel motor support in the form of a horizontal partition drip pan, having air openings and moisture eliminators therein to thereby trap any moisture or liquid that may be released from or by reason of the core.

Another object of the invention is to provide a novel fan and motor arrangement under the partition pan and support them thereby, thus to provide a simple, efficient and low cost air circulating means.

And further, an object is to provide a simple and light unit that may if desired, be easily and detachably mounted on the wall of the room served and to provide a simple detachable mounting for the heating or cooling core whereby it may be easily removed and replaced.

To these and other useful ends my invention consists in matter hereinafter set forth and claimed and shown in the accompanying drawings in which:

Figure 1 is a front sectional elevation of the device taken on line 1—1 of Figure 3.

Figure 2 is a top plan view of the housing cover.

Figure 3 is a side elevation of the device shown in Figure 1, taken on line 3—3 of Figure 1.

Figure 4 is a top view of the transverse partition or pan which acts as a motor, fan and eliminator support.

Figure 5 is a transverse, fractional, sectional view of the pan and eliminator taken on line 5—5 of Figure 3.

Figure 6 is a fractional section of the pan and eliminator taken on line 6—6 of Figure 1.

Figure 7 is a vertical transverse section of the housing cover and its grille taken on line 7—7 of Figure 2.

Figure 8 is a front elevation of the housing less the top cover, detachable front panel, core, 10 motor and fans.

Figure 9 is a side elevation of the housing as shown in Figure 8.

Figure 10 is an enlarged fractional section taken on line 10—10 of Figure 9, including a 15 fraction of the front panel.

Figure 11 is a fractional rear view of the housing supporting strip.

Figure 12 is an end view of the supporting strip.

Figure 13 is a diagrammatic illustration of a 20 modification.

As thus illustrated the reference character A designates the core in its entirety, B designates the motor, C—C designate the blower fans and D—D designate, in their entirety, the moisture 25 eliminators.

Reference numeral 1 designates the rear panel of the housing and 2—2 the side panels, each having inwardly turned portions 3—3. Portions 3 are bent as at 4 (see Figure 10) forming narrow strips 5, having inwardly turned flanges 6—6. The opening left between strips 5 is supplied with a panel 7. This panel is bent on each side as at 8, forming flanges 9, each of which is adapted to rest on portions 6 whereby member 7 is held on the same plane as members 3; thus when panel 7 is in position, a complete vertical, rectangular chamber is provided.

I provide threaded nuts 12 which are suitably positioned and spot welded in spaced apart relation on members 6. Registering openings are provided in members 6 and registering openings are provided in panel 7 for screws 13 whereby the panel 7 may be securely but removably attached to the body of the housing.

I provide a top cover 15 for the housing, having suitable overhanging flanges and preferably three air outlet openings as clearly shown in Figures 2 and 7. I provide novel grilles for these openings, the center sections of which are provided with 50 closely spaced, narrow, transverse strips 16, preferably positioned as shown in Figure 7, to thereby direct the air vertically. The end openings are provided with grilles whose strips 17 are likewise transversely positioned and closely spaced as in- 55

dicated. These strips 17 are, however, preferably positioned at diverging angles to thereby direct the air current outwardly, as indicated by arrows in Figure 7.

5 Thus it will be seen that the circulated air will be discharged fan like. It will therefore spread and move outwardly toward the opposite side of the room and downwardly and turn back at and near the floor and re-enter the cabinet at its bottom as at 18.

10 Clearly there will be a soft movement of air through the room, imperceptible to the occupants but the movement will be complete so there is a frequent and complete change of air over the 15 entire area of the room. Obviously, one of my cabinets will serve perfectly a medium sized room. For larger rooms two or more cabinets may be 20 suitably positioned in the room. I may obviously, position the air outlet and grilles at a transverse angle in the lid or in the front of the cabinet, thereby to discharge the air into the room but in some other direction than shown in the drawings. I may also elect to provide vertically positioned 25 risers through which to convey the air a distance above the cabinet.

Clearly my cabinet may be provided with supporting feet. I prefer, however, to mount the cabinet at a proper height on the wall. For this purpose I provide two spaced apart U shaped vertically positioned strips 20 having outwardly projecting flanges 21-21, which are spot welded to the rear panel of the housing.

These strips are provided with a suitable number of orifices 22 and upwardly extending narrow slits 23. Thus suitably spaced screws or lag bolts may be placed in the wall so the heads will register with openings 22 whereby when the screw heads enter the openings and the cabinet is lowered, the slits will embrace the body of the screws 40 and the cabinet will be securely held into position.

45 Thus I have described my cabinet and its cover lid and grilles whereby, when air is discharged, it will circulate in a manner which insures maximum comfort for the occupants in the room served.

I provide means in the cabinet for circulating air therethrough and conditioning this air as follows:

The core A comprises preferably four rows of 50 tubes each row having four tubes. The tubes of each row are connected in series by means of loops 32 and the rows are serially connected by means of loops 33, whereby the heating or cooling medium has a single tube passage through the core, 55 the inlet tube 30 having a connection to the open end of the top row of tubes as at 31; therefore the operation will be on the counter flow principle, viz., the heating or cooling medium will enter the top row of tubes and pass downward through each 60 succeeding row of tubes and the air enters the core at the bottom and is discharged from the top row of tubes. The outlet end of the bottom row of tubes is connected to the outlet tube 35 as at 36. Thus it will be seen that the cooling or 65 heating medium may enter and pass through each transverse row of tubes sinuously.

The tubes are supplied with a multiplicity of 70 closely spaced fins 38, thus providing an efficient heat transfer core. I provide sheet steel header plates 39-39 through which the enlarged ends of the tubes protrude slightly and are bonded thereto. The lower edges of plates 39 are provided with outwardly projecting portions 40-40 thereby to stiffen the plate and provide supporting feet 75 for the core.

A U shaped bracket 45, made from sheet steel, is, at its base, attached to the side members 2 of the housing, as shown in Figure 1. Members 40 rest upon and are detachably made fast to the upper flanges of members 45, the lower flanges 5 acting as supports for pan 50 which in turn, co-operating with the lower flanges, act as a partition, separating the housing into two compartments. This pan, at its ends, is detachably secured to the lower flanges of members 45 as 10 clearly indicated in Figure 1.

I provide an electric motor B having extended shaft ends upon which the rotors (not shown) of fans C are mounted; this motor is secured to the under side of pan 50 as indicated in Figure 1, 15 the connection being formed preferably by means of four bolts 51, through suitable steel and rubber washers 52 and suitable nuts, thus to seal against leakage and to muffle any sound that may be caused by the action of the motor. 20

The fan housings are secured to the under side of the pan 50 as indicated in Figures 1 and 3, the pan having registering openings with the air outlet of the fan. These openings are designated by reference characters 53-53 and are surrounded on three sides by angle irons 54 and 25 55. The vertical flanges of angles 54 join the pan sides as at 56, so as to form a vertical air passageway, the walls of which are about one half the depth of the pan (see Figure 5). It 30 will be noted that there is left a space between the angle iron 55 and the front wall of the pan as at 57 (see Figures 3 and 6); thus the remaining bottom of the pan is open for the flow of the condensate. 35

It will be seen that the upper flanges of brackets 45 and members 39 and 40 form an air lock between the ends of the core A and the housing walls whereby air cannot pass through the cabinet except through openings between the fins 38 40 of the core and between the end fins and header plates 39. The lower flanges of brackets 45 also act to form an air lock between the ends of the pan and the housing. It will also be seen that the pan ends extend a short distance under members 40; thus condensate that may be formed outside the plates 39, may drop into the pan through openings 41. I provide upturned flanges on the ends of members 40 to form a collecting trench for such condensate. 45

50 Between one of the channels 55 and the pan wall, I preferably provide an under hanging trough designated by numeral 58 (see Figures 1 and 6). A registering opening may be made in the pan bottom or the pan bottom may extend 55 over this trough, having one or more openings whereby the condensate may drain into the trough.

I provide a flanged bracket 59 providing a connecting means for drain pipe 60. This pipe may 60 be arranged for drainage in any suitable manner or a valve may be provided whereby the condensate may be permitted to accumulate in the trough 58 and drain at intermittent periods.

I provide eliminators as follows: Plates 65 are 65 positioned transversely over openings 53, the bottoms resting on the upper edge of angles 55 and the ends, at their lower sides, being bent at right angle and secured to the pan sides by bonding, the upper portion of this joint stopping short of 70 the pan top, thus to prevent any condensate from flowing from plate 65 over the edge of the pan. These plates are spaced apart a suitable distance and positioned at an angle as illustrated in Figures 1 and 5, thus to overlap vertically whereby 75

drippings may not fall from core A into openings 53.

At the bottom edge of plates 65 I provide an upwardly folded edge 66 (see Figure 5), thus forming a trench which is closed at the rear end and left open at the other end as at 67, thus to direct the condensate into the pan at 57. The trench formed by upturned edges 66 is positioned at an angle to the pan as indicated in Figure 6. 10 Thus it will be seen that the condensate will drop on plates 65 and flow into these trenches and then into the pan from whence it will flow to trough 58.

When the motor is in operation the air will pass into the bottom of the cabinet at 18, thence into the fans as indicated by arrows, thence through openings 53 and between the plates 65, to and through the core A and through the grilles as further indicated by arrows. Obviously the drippings will either fall in the pan or be directed thereto by the eliminators and the circulated air will be heated or cooled, depending upon the medium forced through the tubes of core A. I contemplate using the design shown for cooling by a refrigerant or brine and for heating by means 25 of heated water. Obviously other forms of cores may be supplied to accommodate the various mediums to be passed therethrough.

By removing panel 7, all of the units will be in view and if desired, the core, motor or fans 30 may be easily removed or the pan and all parts attached thereto removed intact. It will be noted that the lid 15 may also be easily removed and replaced.

Referring now to Figure 13. This design, other 35 than the fan and motor may be exactly like the design shown in the other figures. The design and position of the fan and motor being particularly suited for small, low cost units or square or circular housing units having a single fan and 40 eliminator.

Referring to the various figures, it will be noted that I provide a temperature insulator 70 for the inner surface of a portion of the cabinet beginning 45 preferably at the top of the pan and extending to the top of the housing. This insulating material is made into slabs and suitably shaped so it may be easily attached to members 1, 2, 3 and 7, before the detachable parts have been assembled into the housing.

50 Thus it will be seen that I have provided a simple, inexpensive and economical heating or cooling unit, easily assembled, installed or inspected and that the temperature transfer is by counter flow, thus to provide maximum efficiency.

55 Having thus shown and described the preferred form of my invention, I claim:

1. An air conditioner, comprising a vertically

positioned cabinet having a rectangular shape in cross section, the front panel of said cabinet being removably attached, unitary U shaped sheet steel brackets attached to the side walls of said cabinet the end flanges projecting inwardly, a cooling core having outwardly projecting header plate flanges adapted to rest on the upper flanges of said brackets and be removably attached thereto, said supporting and header plate flanges adapted to prevent the passage of air between said side 10 walls and said core, a motor and fan supporting partition wall adapted to rest on the lower inwardly projecting flanges of said brackets, an opening in said partition wall registering with the discharge opening of said fan, an air inlet at the 15 bottom of said cabinet and an air outlet at the top thereof whereby air may be circulated from said inlet through said partition opening and through said core.

2. An air conditioner of the class described, 20 comprising a vertically positioned cabinet having a rectangular shape in cross section, the front panel of said cabinet being removably attached, upper brackets on each end wall of said cabinet, lower inwardly projecting brackets on each end 25 wall of said cabinet, a cooling core having header plates supported by said upper brackets and cooperating therewith to prevent the passage of air except between the tubes of said core, a liquid tight pan supported by said lower brackets, a 30 motor supported from the bottom side of said pan, air propelling fans supported by said pan and positioned on opposite sides of said motor and operatively connected thereto, said fans having air outlets through and extending a distance 35 above the bottom of said pan, eliminators positioned above said air outlets having means whereby the condensed moisture caught will drain by gravity into said pan.

3. A device of the class described, comprising a 40 vertically positioned housing having an air inlet at its bottom and an air outlet at the top thereof, a cooling core adjacent said air outlet having supporting means adapted to cooperate with the header plates of said core and act as an air lock 45 between the walls of said housing and the finned surface of said core, a partition between said air inlet and said core comprising a liquid tight pan and supporting brackets, said brackets attached to the walls of said housing, a fan motor supported by said pan from the under side thereof, an air outlet for said fan extending through and a distance above the bottom of said pan, eliminators positioned above said air outlet having means whereby condensed moisture caught will 50 55 be drained by gravity into said pan.

FRED M. YOUNG.
